CLAIM

The ornamental design for a wheel spoke insert as shown and described.

DESCRIPTION

FIG. 1 is a perspective view of a wheel spoke insert; FIG. 2 is a top plan view of the wheel spoke insert of FIG. 1;

FIG. 3 is a bottom plan view of the wheel spoke insert of FIG. 1;

FIG. 4 is a left-side elevation view of the wheel spoke insert of FIG. 1;

FIG. 5 is a right-side elevation view of the wheel spoke insert of FIG. 1;

FIG. 6 is a front plan view of the wheel spoke insert of FIG. 1;

FIG. 7 is a rear elevation view of the wheel spoke insert of FIG. 1; and,

FIG. 8 is a perspective view of the wheel spoke insert of FIG. 1 installed in a vehicle wheel.

The dash dash broken lines depict portions of the wheel spoke insert and environment that form no part of the claimed design. The dash dot dash broken lines depict boundary lines that form no part of the claimed design.

1 Claim, 8 Drawing Sheets
